Patented Dec. 16, 1919.

FIG. 1.

FIG. 2.

FIG. 3.

UNITED STATES PATENT OFFICE.

CARL OLSEN AND PETER PIMLOTT, OF BROOKLYN, NEW YORK.

GAS-BURNER.

1,325,370.

Specification of Letters Patent. Patented Dec. 16, 1919.

Application filed August 16, 1918. Serial No. 250,148.

To all whom it may concern:

Be it known that we, CARL OLSEN and PETER PIMLOTT, citizens of the United States, residing at Brooklyn, in the county 5 of Kings and State of New York, have invented certain new and useful Improvements in Gas-Burners, of which the following is a specification.

This invention relates to improvements 10 in liquid and gaseous fuel burners, and it is the principal object of the invention to provide a fuel burner of the superheating type whereby the fuel supplied thereto is reduced to a highly combustible gas during its passage 15 over the burner flame and is then supplied to the burner for combustion.

Another and equally important object of the invention is to provide the burner with a form of gas pressure equalizing means into 20 which the gas generated by the burner is discharged and permitted to pass to the burner proper in such a manner as to produce an even and uniform flame.

It is also an object of the invention to provide 25 the retort portion of the burner with means for preventing the back flow of gas therefrom, hence, insuring the production of an effectual flame at the burner.

The improvements in the details and arrangement of parts will be apparent from an 30 inspection of the accompanying drawings, in connection with the specific description hereinafter contained, and wherein the preferred embodiment of the invention is described 35 closed for the purpose of imparting a full understanding thereof.

In the drawings:

Figure 1 is a top plan of the burner, Fig. 2 is a longitudinal section there- 40 through, and

Fig. 3 is a transverse section through the same.

Referring more specifically to the drawings, in connection with which like reference characters will designate corresponding parts throughout the several views, 1 represents the retort of the burner, the same consisting of a pipe coil, one extremity of which is raised above the main portion of the coil 45 as indicated at 2 and is tapped into the upper end of a pressure equalizing conduit or chamber 3, the lower end of this chamber having one end of a burner pipe 4 tapped thereinto, which pipe, as will be noted, is 50 formed with a plurality of longitudinally

arranged burner openings 5. In this connection, it is to be noted that the burner pipe 4 is arranged directly under the retort chamber formed by the pipe coil 1 and that the upper extremity 2 of the pipe coil is 60 provided with a suitable form of adjustable flame deflector 6, for an obvious purpose.

Engaged with the remaining or free end of the retort chamber or pipe coil is a check valve 7 having a suitable form of nozzle 65 8 connected thereto whereby to reduce the flow of fuel into the retort chamber in order that the same can be reduced to gas in the least possible time to a combustible gas. It of course will be understood that the check 70 valve 7 has connection with a suitable form of supply pipe 9 extending from a reservoir or other source of supply, not shown, further, that if desired, suitable cut-off means, not shown, can be interposed in the supply 75 pipe 9 whereby to regulate flow of fuel to the burner.

For starting the burner, a fuel pan 10 is provided and is arranged under the burner pipe 4 and secured thereto by passing metal 80 straps 11 over the same and engaging their opposite ends with portions of the pan. Into this pan, a suitable form of combustible liquid is placed and when ignited will heat the liquid fuel passing through the retort 85 chamber to an extent to cause its reduction to combustible gas for ignition at the burner openings of the burner pipe 4. Due to the manner in which the liquid fuel is discharged into the retort chamber or pipe coil 90 1, it will be understood that reduction of the same to gas by heating of the pipe coil can be accomplished in the least possible time.

The gas generated in the retort chamber of pipe coil upon operation of the burner is 95 discharged therefrom into the equalizing chamber 3, which as hereinbefore stated, is of a diameter greater than the diameter of the pipes forming the retort. As a consequence, the gas discharged from the equalizing 100 chamber into the burner pipe 4 will be under an even and uniform pressure and in consequence, an even and uniform flame will be produced thereby. Back pressure of the gas when generated will be prevented 105 due to the positioning of the check valve 7 therein, insuring proper functioning of the burner.

Manifestly, the construction shown is capable of considerable modification and such 110

modification as is within the scope of our claims, we consider within the spirit of our invention.

We claim:

- 5 The combination with a fuel pan, of a gas burner comprising a hollow body forming a pressure equalizing chamber resting within the pan at one end thereof, a burner pipe tapped into the hollow body near the lower end thereof and extending normal thereto, and a retort including a coil pipe having spaced parallel stretchers, one of said
- 10

stretchers being tapped into the upper portion of the hollow body, and the other stretchers extended on opposite sides of said body and about the same, the first named stretcher of the coil being disposed superposed relative to the burner pipe and directly over the same in parallel relation thereto.

In testimony whereof we affix our signatures hereto.

CARL OLSEN.
PETER PIMLOTT.
